UNITED STATES PATENT OFFICE.

WILLIAM ANDREW MORRISON AND FREDERICK DELIMER LAKE, OF ST. CATHERINES,
ONTARIO, CANADA.

ELECTRIC HEATER.

1,389,684. Specification of Letters Patent, or Patented Sept. 6, 1921.

Application filed October 4, 1920. Serial No. 414,629.

To all whom it may concern:

Be it known that we, WILLIAM ANDREW MORRISON and FREDERICK DELIMER LAKE, of the city of St. Catharines, in the county of 5 Lincoln, in the Province of Ontario, Canada, have invented certain new and useful Improvements in Electric Heaters, of which the following is the specification.

Our invention relates to improvements in 10 electric heaters and the object of the invention is to devise a simple, cheap, compact, highly efficient form of heater particularly adaptable for use in hot water boilers in which the electric element may be quickly 15 and easily removed for the purpose of repair without damage to any part of the heater and it consists essentially of the following arrangement and construction of parts as hereinafter more particularly explained.

Figure 1 is a sectional plan view of a boiler showing our electric heater in place.

Fig. 2 is a longitudinal sectional view through our heater intermediately broken 25 away of its length.

Fig. 3 is a sectional view on line 3—3 Fig. 2.

Fig. 4 is a sectional view on line 4—4 looking at the end of the electric element.

Fig. 5 is a detail of the core forming the base of our electric element intermediately broken away of its length.

In the drawings like characters of reference indicate the corresponding parts in each 35 figure.

1 indicates a boiler which is filled in the usual manner with water 2. 3 indicates an internally threaded orifice into which our electric heater is adapted to be screwed so 40 as to extend diametrically across the boiler 1.

4 indicates a cylindrical casing, the exterior surface of which is provided with a square thread 5 cut therein extending from end to end. The purpose of this thread is to prevent 45 the deposits from the water from permanently coating the heater casing and destroying the efficiency of the heater. By providing a square thread as indicated, the expansion or contraction of the cylinder as

50 the water becomes hot or cold serves to scale off these deposits by reason of the surfaces of the thread extending at right angles one to the other. 7 is a closing cap screwed or otherwise suitably secured to the open end 55 of the casing. The cap 7 is provided with

an external thread 8 adapted to be screwed into the internally threaded orifice 3 of the boiler. The outer end of the cap 7 is provided with a nut portion 9 formed integral with the cap and at its inner end with an annular recess 10 into which the reduced portion 6 of the cylindrical casing 4 fits and is suitably secured. The casing 4 is preferably made of copper or other suitable heat conducting material and is closed at its opposite end by a copper disk 11 which is brazed in the open inner end of the casing. 18 indicates a core of soapstone or other material adapted to absorb and maintain heat to a maximum extent. The core is cylindrical in form and has a double square thread 19 cut therein to contain windings of the element. 20 and 21 indicate recesses cut in the outer end of the core and extending longitudinally thereof, the upper end of one convolution of the thread 19 opening into the inner end of the recess 20 and the other convolution opening into the recess 21. 22 and 23 indicate the copper leading in wires which extend from orifices 24 and 25 formed in the nut shaped end 9 of the cap 7. The inner ends of the wires 22 and 23 extend into the recesses 20 and 21. 29 indicates the winding of my heat element and is formed of nichrome wire. One end of the wire extends from the recess 20 and passes longitudinally of the core through one convolution of the double thread to the inner end of the core and then extends through the diametrically extending groove 26 to the opposite side of the core and there enters the other convolution of the double thread passing longitudinally through such convolution to the recess 21.

It will thus be seen that by this arrangement that the turns of that portion of the wire leading in are arranged alternately to that portion of wire leading out. The wires 22 and 23 are connected to the ends of the wire 24 by suitable coupling sleeves 27 and 28 which are embedded in a filling of dielectric cement 30 contained in the recesses 20 and 21. The cap 7 may be threaded or otherwise suitably secured to the casing 4 or attached by any other means permitting their easy and quick separation to enable the electric element 18 being withdrawn for the purpose of repair when necessary.

From this description it will be seen that we have devised a very simple, cheap, easily

- installed electric water heater particularly adaptable for use in a domestic hot water boiler and which may be easily and quickly repaired whenever it becomes necessary and 5 which will produce a very high temperature and therefore is efficient and at the same time is compact, taking up no space outside of the boiler such as is common with ordinary electric water heaters.
10. What we claim as our invention is.
1. An electric water heater comprising a cylindrical casing of heat conducting material adapted to be inserted in an orifice in a boiler wall and to extend inwardly into 15 the boiler, a core formed of heat absorbing material fitting within the casing and provided with a double thread extending longitudinally thereof, and a winding formed by a wire extending inwardly longitudinally of 20 the core through one member of the double thread and returning outward through the other member of the double thread and adapted to be secured at its ends to leading in wires.
  25. 2. In an electric water heater, a tubular casing formed of heat conducting material, a removable cap secured to the outer end of the casing having orifices for leading in wires and provided with an external thread, 30 a core of heat absorbing material fitting within the cylindrical casing and having a double thread extending longitudinally thereof, and a diametric groove connecting the inner ends of the members of the double 35 thread and wire winding adapted to extend inwardly through one member of the double thread through the diametric groove at the

inner end of the core and then outward through the other member of the double thread. 40

3. In an electric water heater, a cylindrical casing formed of heat conducting material, a removable cap for the casing, a core of heat absorbing material provided with a double thread extending longitudinally thereof 45 and at its inner end with a diametric groove connecting the inner ends of the thread and at its outer end with longitudinal recesses into each of which the member of the double thread enters, leading in wires extending 50 through the cap into the recesses, a wire winding connected at one end to one leading in wire in one recess and extending longitudinally of the core through one member of the double thread, then through the diametric spot, then returning through the other member of the double thread into the other recess, and a cement filling for the recess. 55

4. The combination with a boiler wall having an interiorly threaded orifice, of a heating element comprising a cylindrical casing having a threaded portion adapted to be screwed into the thread of the boiler orifice so as to support the casing extending into the interior of the boiler, and a heating element comprising a core of heat absorbing material, and a winding wrapped around the core so as to extend from end to end thereof with both ends extending outwardly from the outer end of the core, and means for 70 connecting the leading in wires thereto. 60 65
